DESIGN FOR A FENCE

Carl M. Schubert, San Francisco, Calif.

Application March 18, 1941, Serial No. 99,670

Term of patent 3½ years

To all whom it may concern:

Be it known that I, Carl M. Schubert, a citizen of Germany, residing at San Francisco, in the city and county of San Francisco and State of California, have invented a new, original, and ornamental Design for a Fence, of which the following is a specification, reference being had to the accompanying drawing, forming a part thereof.

Fig. 1 is a front elevational view of a portion of a fence, showing my new design,

Fig. 2 is a top plan view of the same.

I claim:

The ornamental design for a fence, as shown.

CARL M. SCHUBERT.
